Patented Feb. 18, 1919.

2 SHEETS--SHEET 2.

UNITED STATES PATENT OFFICE.

JOSEPH HENBA, OF BROOKLYN, NEW YORK.

MOTOR-PROPELLED BALLOON.

1,294,661.

Specification of Letters Patent. Patented Feb. 18, 1919.

Application filed September 19, 1918. Serial No. 254,776.

To all whom it may concern:

Be it known that I, JOSEPH HENBA, a citizen of the Republic of Russia, and resident of the borough of Brooklyn, in the city and State of New York, have invented a new and useful Improvement in Motor-Propelled Balloons, of which the following is a specification.

The object of my invention is to provide means whereby the car which is suspended from the balloon is automatically maintained in its horizontal position irrespective of the location of the weight on the car.

Another object is to so suspend the car from the balloon that the car will be maintained in a horizontal position as the balloon tilts and rolls to different positions.

A still further object is to provide auxiliary propelling means located beneath and in proximity to the nose of the balloon.

A practical embodiment of my invention is represented in the accompanying drawings, in which—

Figure 1 represents the balloon in side elevation part of the side of the car being broken away,

Fig. 2 is a detail vertical section taken from front to rear through the car and a suspending means,

Fig. 3 is a front view of the balloon, a portion of the front of the car being broken away,

Fig. 4 is a horizontal section through the car, taken in the plane of the line IV—IV of Fig. 1,

Fig. 5 is a detail side view on an enlarged scale, showing the parts at the upper end of the car suspending bar,

Fig. 6 is a similar view in front elevation, and

Fig. 7 is a detail section on an enlarged scale, showing the way in which the counter-balance tank for the car maintains the car in its horizontal position, when weight is applied to the rear end of the car.

The balloon is denoted by 1. It may be of the usual oblong shape, provided with vertical and horizontal rudders 2, 3, and the front and rear horizontal wings 4, 5.

A car suspending bar 6 has a universal joint connection 7 at its upper end with the encircling band 8 of the balloon. It also has a universal joint connection 9 with the top of the compensating tank 10. This tank 10 is rectangular in shape and quite shallow and is adapted to contain a liquid 11.

The car 12 is provided with a suitable deck 13 having a superstructure 14. This car not only incloses the tank 10 but also a horizontal platform 15 located between the tank 10 and the deck 13.

A series of radially arranged levers 16 are fulcrumed at 17 to the platform 15. The inner ends of these levers are connected by links 18 to the under side of the deck 13. The outer ends of these levers are connected by links 19 to the top of the tank 10.

The car is connected to a platform 20 carried by the bar 6 above the car, by means of a peripheral series of vertical bars 21, secured at their lower ends to the platform 15 and projecting upwardly through the deck 13. The upper ends of these rods are attached to flexible connections 22, which pass around pulleys 23 on the platform 20 and have their other ends secured to the deck 13 of the car. Springs 24 surround the rods 21 between the deck 13 and the platform 15.

The platform 20 is rigidly maintained in position on the bar 6 by a series of inner braces 25, 26, and a series of outer braces 27.

The car is provided with four suitable side frames 28, in the lower ends of which are journaled traction wheels 29.

Two propelling means are mounted on the platform 20. In the present instance I have shown two front screw propellers 30 and their engines mounted upon opposite sides of a pilot-house 31. This platform 20 may also carry the fuel tank 32.

Auxiliary propelling means are provided beneath and in proximity to the nose of the balloon, which propelling means are herein shown as two screw propellers 33, and their engines located upon opposite sides of a pilot-house 34, carried by a platform 35 rigidly secured to the balloon by suitable guys and rods 36, 37. A ladder 38 may be used as a means of connection between the platform 20 and the platform 35.

The compensating connection between the platform 20 and the balloon whereby the platform and its suspending car are maintained in a substantially horizontal position irrespective of the tilting and rolling action of the balloon, is herein shown as a system of longitudinal and transverse guys 39, 40, secured to the platform 20 and passing over a series of pulleys 41, located at different points along the body of the balloon. The longitudinal guys all pass over

pulleys 42 carried by the encircling band 8 in the transverse plane of the car supporting bar 6.

From the above description, it will be seen that the auxiliary propelling means located beneath and in proximity to the nose of the balloon, is connected rigidly to the balloon. It will also be seen that the car is maintained in a substantially stable equilibrium as the balloon tilts or rolls. It will also be seen that the lever connection between the compensating tank 10 and the deck 13 of the car will maintain the car in a horizontal position when the weight of the car is distributed unevenly:

It is evident that slight changes may be resorted to in the form, construction and arrangement of the several parts without departing from the spirit and scope of my invention; hence I do not wish to limit myself strictly to the structure herein set forth, but

What I claim is:—

1. In a motor propelled balloon, a car flexibly suspended from the balloon, and automatically acting liquid controlled counterbalancing means for maintaining the car in a horizontal position when weight is distributed unevenly thereon, said means including a horizontally arranged liquid carrying shallow tank and compensating connections between the tank and car.

2. In a motor propelled balloon, a car suspended from the balloon, and counterbalancing means for maintaining the car in a horizontal position when weight is distributed unevenly thereon, said means including a horizontally arranged liquid carrying shallow tank, a platform interposed between the tank and car deck, and a series of radiating levers fulcrumed on the platform and connected at their outer and inner ends respectively to the tank and car deck.

3. In a motor propelled balloon, a car suspended from the balloon, and counterbalancing means for maintaining the car in a horizontal position when weight is distributed unevenly thereon, said means including upper and lower platforms, flexible connections between them and the car deck, a horizon-

tally arranged liquid carrying shallow tank located beneath the lower platform, and a series of radiating levers fulcrumed on the lower platform and connected at their outer and inner ends respectively to the tank and car deck.

4. In a motor propelled balloon, a car suspended from the balloon, and counterbalancing means for maintaining the car in a horizontal position when weight is distributed unevenly thereon, said means including a liquid carrying tank, a suspending bar flexibly connected at its upper and lower ends respectively to the balloon and tank, and compensating connections between the tank and car.

5. In a motor propelled balloon, a car suspended from the balloon, and counterbalancing means for maintaining the car in a horizontal position when weight is distributed unevenly thereon, said means including a liquid carrying tank, a suspending bar flexibly connected at its upper and lower ends respectively to the balloon and tank, an upper platform fixed to the bar, a lower platform flexibly connected to the car deck and upper platform, and a system of radiating levers fulcrumed on the lower platform and connected at their outer and inner ends respectively to the tank and car deck.

6. In a motor propelled balloon, a car suspended from the balloon, and counterbalancing means for maintaining the car in a horizontal position when weight is distributed unevenly thereon, said means including a liquid carrying tank, a suspending bar flexibly connected at its upper and lower ends respectively to the balloon and tank, an upper platform fixed to the bar above the car, a lower platform located between the car deck and tank, a peripheral series of flexible connections between the two platforms and car deck, and a system of radiating levers fulcrumed on the lower platform and connected at their outer and inner ends respectively to the tank and car deck.

In testimony that I claim the foregoing as my invention I have signed my name this 17th day of September, 1918.

JOSEPH HENBA.
